UNITED STATES PATENT OFFICE

WENDYL R. MEDLOCK, OF POCATELLO, IDAHO, ASSIGNOR OF TWENTY-FOUR AND ONE-HALF PER CENT TO PERCY B. GLASSER AND TWENTY-FOUR AND ONE-HALF PER CENT TO WILLIAM W. GOODMAN, BOTH OF POCATELLO, IDAHO

TEAR GAS GUN

Application filed December 11, 1931. Serial No. 580,447.

The object of the invention is to provide a device particularly adapted for the support of the gas shell and the explosion of the latter through a simple pulling operation effected by the fingers of the hand while the device is held against the palm thereof; and to provide a device of this nature which is of simple form, composed of but few parts and susceptible of cheap manufacture.

With this object in view, the invention consists in a construction and combination of parts of which a preferred embodiment is illustrated in the accompanying drawing. Actual reduction to practice, however, may dictate certain changes or alterations in the present embodiment and the right is claimed to make any which fall within the scope of the appended claims.

In the drawing

Figure 1 is a central vertical sectional view of a gas gun constructed in accordance with the invention.

Figure 2 is a sectional view on the plane indicated by the line 2—2 of Figure 1.

Figure 3 is an elevational view of the carrier sleeve.

Figure 4 is another elevational view of the same sleeve but looking in a direction at right angles to that in which Figure 3 is viewed.

Figure 5 is a bottom plan view of the carrier sleeve.

Figure 6 is an edge elevational view of one of the pawls.

Figure 6^a is a front elevational view of the pawl.

Figure 7 is a top plan view of the palm rest.

Figure 8 is an elevational view of the same.

Figure 9 is an elevational view of the firing pin.

Threadingly connected with the upper end of the breech 1 is the barrel 2, the former being reduced in diameter where the threads are formed to provide a shoulder against which the barrel 2 may abut. The barrel 2 is undercut at the upper end of the breech, as indicated at 2^a, to provide a seat for the lower end of the shell when in position, so that the latter may be effectively retained in place in the barrel.

Slidably mounted on the breech is a carrier sleeve 3 which on the bottom end is formed with a crosshead 3^a disposed within the breech below the stop disk 3^b. The breech is formed with slots 3^c to serve as clearance slots for the crosshead, as well as guides for the latter, since the crosshead is carried by the sleeve exterior to the breech.

In the lower end of the breech is inserted the palm rest 4 having diametrically disposed lateral extensions 4^a. This rest is designed to be seated in the palm in the operation of the device and, interior to the breech is formed with a conical depression 4^c which functions to release the pawls 6 from the firing pin 5 in the operation of the device. The firing pin 5 is slidably mounted in the breech and carries the collar 5^a between which and the stop disk 3^b, the spring 7 is compressed.

A second spring 8 is carried in the breech and compressed between the crosshead and the upper end of the palm rest 4.

The sleeve 3 is formed with diametrically disposed finger rests 3^d, so that when the palm rest is disposed in the palm of the hand, certain of the fingers may be disposed on the rest 3^d and the sleeve 3 thus moved down toward the palm rest.

The firing pin is reduced in diameter as indicated at 5^b to provide a shoulder directly behind a conical nose 5^c.

The pawls 6 are two in number and are pivotally mounted in the crosshead at intermediate points in their lengths. The nose portions are yieldingly impelled toward each other by reason of a spring 11 disposed between the tail extensions of the two and seated on tines 11^a.

A blind set screw 10 threaded through the wall of the breech 1, enters the stop disk and effects a fixed attachment between the latter and the breech. The head of this set screw falls within the inner periphery of the sleeve 3 so that it may not interfere with free sliding movement of the latter.

In the operation of the device, the barrel 2 is detached and a shell inserted from the threaded end until the heel portion of the shell engages the seat 2^a. When the barrel is threaded onto the breech the shell is then

retained in position. The spring 7 tends normally to keep the firing pin at the barrel end of the breech, while the spring 8 serves to keep the sleeve 3 in its elevated position, when the noses of the pawls 6 will engage the shoulder at the base end of the conical nose 5^c of the firing pin. Disposing the palm rest in the palm of the hand and engaging the fingers with the finger rests 3^b of the sleeve, the firing pin may be retracted by pulling down on the sleeve (the pawls operatively connecting the firing pin with the sleeve so that it is retracted by the latter) until the tail extensions shall have entered the conical depression or recess 4^c in the palm rest. Continued downward movement of the sleeve will result in the tail extensions of the pawls being moved closer together until finally the noses are withdrawn from the shoulder of the firing pin and its spring 5 will function to drive it against the shell mounted in the barrel which results in the explosion of the shell with the desired result.

The invention having been described, what is claimed as new and useful is:

1. A device of the kind indicated comprising a barrel and connected breech, a firing pin disposed in the breech and spring impelled toward the rear end of the barrel, a sleeve slidably mounted on the breech and having pawls engageable with the firing pin, and a pawl tripping device at that end of the breech remote from the barrel and functioning to disengage the pawl from the firing pin when the sleeve is moved a sufficient distance down the breech, the sleeve being spring impelled in a direction away from the pawl tripping device.
2. A device of the kind indicated comprising a barrel and connected breech, a firing pin disposed in the breech and spring impelled toward the rear end of the barrel, a sleeve slidably mounted on the breech and having pawls engageable with the firing pin, and a pawl tripping device at that end of the breech remote from the barrel and functioning to disengage the pawl from the firing pin when the sleeve is moved a sufficient distance down the breech, the sleeve having a cross-head interior to the breech and the pawls being pivotally mounted in the crosshead for engagement with the firing pin on diametrically opposite sides.
3. A device of the kind indicated comprising a barrel and connected breech, a firing pin disposed in the breech and spring impelled toward the rear end of the barrel, a sleeve slidably mounted on the breech and having pawls engageable with the firing pin, and a pawl tripping device at that end of the breech remote from the barrel and functioning to disengage the pawl from the firing pin when the sleeve is moved a sufficient distance down the breech, the sleeve having a crosshead interior to the breech and the pawls

being pivotally mounted in the crosshead for engagement with the firing pin on diametrically opposite sides, the pawls having firing pin engaging noses above the crosshead and tail extensions below the crosshead, a compression spring disposed between the tail extensions, the pawl releasing means consisting of an element in the lower end of the breech formed with a conical depression in which said tail extensions enter.

In testimony whereof I affix my signature.

WENDYL R. MEDLOCK.
